[57] CLAIM

The ornamental design for a projection television receiver, as shown and described.

DESCRIPTION

FIG. 1 is a front elevational view of a projection television receiver showing our new design;

FIG. 2 is a top plan view thereof;

FIG. 3 is a right side elevational view thereof;

FIG. 4 is a rear elevational view thereof;

FIG. 5 is a bottom plan view thereof;

FIG. 6 is a front, top and right side perspective view thereof; and

FIG. 7 is a perspective view similar to that of FIG. 6 with the hinged cabinet cover in closed position.

*Fig. 1**Fig. 3**Fig. 2**Fig. 4*
